UNITED STATES PATENT OFFICE.

CHARLES ROBERT SAATWEBER, OF PATERSON, NEW JERSEY.

POSITIVE HIGH-SPEED SHUTTLE-MOTION.

1,142,059.

Specification of Letters Patent. Patented June 8, 1915.

Application filed November 28, 1913. Serial No. 803,371.

To all whom it may concern:

Be it known that I, CHARLES R. SAATWEBER, citizen of the United States, residing at 13 Garrison street, in the city of Paterson, in the county of Passaic and State of New Jersey, have invented certain new and useful Improvements in Positive High-Speed Shuttle-Motions, of which the following is a specification, reference being had therein to the accompanying drawing.

My invention relates to improvements in looms for weaving silk, cotton or other fabrics; and the main object of my improvements is to provide a positive high speed shuttle motion, which is without limit, within reason.

Other objects of my improvements are to prevent any undue strain on the filling, to prevent smash-ups and break-downs; to provide a series of intermeshing gears and coating cams all driven from the one shaft to operate the batten and the shuttles at a speed gradually increasing from the starting point to the center and then gradually decreasing to the stopping point in either direction; to prevent the breaking of the filling at the edges of the fabric or to prevent an uneven selvage, which is sometimes caused by the strain upon the filling; to combine in a loom an eccentric shuttle motion and an eccentric batten motion, so as to give the shuttle a chance to start a little sooner and to come home a little later than it otherwise would; to prevent great loss in time and money, and to provide a loom that will turn out work greater in quantity and better in quality.

I attain these objects by the mechanism illustrated in the accompanying drawings, in which—

Figure 1 is a plan view of a portion of a loom showing the relative positions of my improvements, and Fig. 2 is a side elevation of a portion of a loom frame embodying my invention.

In the drawings similar letters and numerals refer to like parts.

Upon the stud A, which is secured to the loom frame, are mounted fast and loose pulleys. Motion is communicated to the fast pulley 3 to which is secured the gear 2. The gear 2 meshes with and imparts motion to the gear 2' on the stud A'. The eccentric gear E is secured to the gear 2' and meshes with the eccentric gear E' which is secured to the main shaft S, re-

volving said shaft S, eccentric E' and the gear 41, which is fixed on said shaft inside the loom frame. From said main shaft S motion is imparted to the batten by means of the driving arm O, one end of which is eccentrically mounted on the stud O', which is secured on the eccentric gear E'. The other end of the driving arm O is adjustably mounted on the stud O², which passes through an elongated slot in a bracket secured to the batten. From the fixed gear 41 on the main shaft S motion is communicated to an intermeshing gear 42, which is mounted to revolve on the stud B, and thence to the intermeshing gear 43, which is secured to the shaft R inside the loom frame. Actuating cams R' and R² are also secured to said shaft R outside the frame, side by side, and alternately engage the rollers 5 and 7 which rotate in brackets on the treadles T and T'. Said treadles T and T' are connected with the smaller portions of the double pulleys P, which rotate on the stud P', by straps M. There are a pair of said double pulleys located side by side, each being provided with a circumferential groove on both the larger and smaller portions thereof. The ends of straps C are secured in said grooves around the larger portions of the double pulleys, and pass thence around the pulleys D in the lower portion of the loom frame, and thence upward substantially perpendicularly, when the batten is in the center or midway of its course, each strap passing over one of the rollers —a—, one strap passing to the right and the other strap passing to the left in a groove in the body of the batten beneath the rack to which they are secured. The shuttles —s— are thus operated by the rack and pinions. When the cam R' engages the roller 5, pushing the treadle T backward, the cam R² permits the treadle T' to recede and the straps C are thus alternately pulled, giving the reciprocating movement to the rack, which is imparted to the shuttles —s— through the coöperation of the ordinary or usual pinions.

Only one shuttle is shown in the drawings, it not being deemed necessary to show more than that. It will be obvious, therefore, that there is never any slack straps, when one recedes, the other advances. For instance, referring to Fig. 2, the cam R' by engaging the roller 5 has pushed the treadle T back and by so doing has unwound its

strap M from the small portion of its double pulley P, causing the double pulley P to turn, thereby winding its strap C on the larger portion of the double pulley P; and 5 referring to the same figure, the cam R' has simultaneously permitted the treadle T' to move in the opposite direction, its strap M being wound on to the smaller portion of its double pulley P, which rotates in an opposite direction from its twin pulley P, and the other strap C is unwound from the larger portion of its pulley P. The cams R' and R² and the rollers 5 and 7 may be provided with teeth, without departing from the scope 10 of my invention.

By the construction herein described and shown in the drawings, any desirable speed may be obtained without imparting a jerky motion, and I obtain a positive high speed 20 shuttle motion which will prove a great advantage in many ways. It will be especially useful when filling of an inferior quality is employed, because it will obviate breaks and smash-ups.

25 An essential feature of my invention is the irregular formation of the cams R' and R², which are duplicates, each having the same large arc-shaped engaging surfaces and small arc-shaped engaging surfaces, said 30 arc-shaped engaging surfaces having a common center, and said cams being secured to a common shaft R, so as to alternately operate their respective treadles T and T'. This cam construction enables my device to communicate such a motion through the treadles T and T' and other operative connections to the rack that the shuttles are allowed to lie 35 at rest a portion of the time, while the batten beats the filling up to the fell and while 40 the batten retires half way back before the shuttles start on their return movements through the warp-shed to the opposite side of the ribbon.

As with my shuttle motion the shuttles 45 start off easy and go faster up to the center of their prescribed course and then gradually slow down and go easy at the end thereof, the filling will not drag against the selvage while the lay beats up the filling to the 50 fell, thus obviating any undue strain on the selvage threads, which will result in the production of a better and more uniformly finished fabric.

The eccentric elements of my invention and the combination thereof are capable of 55 various modifications to attain the variable speed required in the driving of the batten and the operating of the shuttles to insure any degree of dwell or rest required preparatory to the flight of the shuttles in 60 either direction, without departing from the essential spirit or scope of my invention.

With this description of my invention, what I claim as new and desire to secure by Letters-Patent, is:

1. In a loom, the combination with the frame, the batten carrying rack and pinions and shuttles, operatively connected with a pair of treadles fulcrumed in the lower portion of said frame, of a driving shaft and 70 actuating connections including eccentrics to drive from the shaft both the batten and the rack, communicating to each a variable speed, substantially as set forth.

2. In a positive high speed shuttle motion 75 for looms, the combination with the frame, the batten, shuttles, rack and pinions carried by the batten, main driving shaft and eccentric driving connections between said driving shaft and the batten to communicate a variable speed to the batten, of treadles, connections between said treadles and the rack, a cam shaft mounted in said frame, a gear secured to said cam shaft inside the loom-frame, twin actuating cams oppositely 80 arranged and secured to said cam shaft outside the loom-frame and adapted to alternately operate said treadles, a fixed gear on main driving shaft, an intermeshing gear connecting the fixed gear on the main shaft 85 and the fixed gear on the cam shaft, an eccentrically arranged gear secured to the main shaft, a gear having an eccentrically arranged elliptical gear secured thereto and adapted to mesh with the eccentric gear secured on the main shaft and means for communicating power to said series of gears whereby the main shaft is driven at a variable speed so as to drive the shuttles at a variable speed, substantially as set forth. 95

In testimony whereof I affix my signature in presence of two witnesses.

CHARLES ROBERT SAATWEBER.
